Specification for Design.

Patented July 18, 1911.

Application filed April 25, 1911. Serial No. 623,326. Term of patent 3½ years.

To all whom it may concern:

Be it known that we, EDMUND P. HADLEY and CROFTON C. HOLDEN, citizens of the United States of America, residing at Leominster, in the county of Worcester and State of Massachusetts, have invented a new, original, and ornamental Design for Brush-Holders; and we do declare the following to be a full, clear, and exact specification of the same.

Our invention relates to a design for brush holders, which is illustrated in the accompanying drawing, in which the figure is an elevation of a brush holder, showing our new design.

We claim,

The ornamental design for a brush holder,—as shown.

EDMUND P. HADLEY.
CROFTON C. HOLDEN.
